UNITED STATES PATENT OFFICE.

GEORGE W. TANNER, OF PROVIDENCE, RHODE ISLAND.

DESIGN FOR A CIGAR OR CIGARETTE CASE.

SPECIFICATION forming part of Design No. 19,667, dated February 25, 1890.

Application filed October 31, 1889. Serial No. 328,849. Term of patent 7 years.

To all whom it may concern:

Be it known that I, GEORGE W. TANNER, a citizen of the United States, residing at Providence, in the county of Providence and State of Rhode Island, have invented and produced a new and original Design for Cigar or Cigarette Cases, of which the following is a specification, reference being had to the accompanying drawings, forming part thereof.

10 In the drawings, Figure 1 is a view of one of the two sides of a cigar or cigarette case showing my design, and Fig. 2 is a sectional view of the same.

The leading feature of my design consists 15 in the form of the case of approximately rectangular section, having the configuration of the open human hand.

A is the palm portion of the hand. b b b are the fingers, and c the thumb. The palm portion, the fingers, and the thumb have the 20 rounded surface of these members of an open human hand. The cross-section of the case is of approximately rectangular form, as is shown in Fig. 2.

What I claim is—

25 The design of a cigar or cigarette case herein shown and described, the same having the outline and configuration of an open human hand of approximately rectangular cross-section, as set forth.

GEORGE W. TANNER.
